(57) **CLAIM**

I claim the ornamental design for a door handle and striker, as shown and described.

DESCRIPTION

FIG. 1 is a front perspective view of a door handle and striker according to my new design;

FIG. 2 is a rear perspective view of the door handle of FIG. 1;

FIG. 3 is a rear plain view of the door handle of FIG. 1;

FIG. 4 is a side elevational view of the door handle of FIG. 1;

FIG. 5 is a front plain view of the door handle of FIG. 1; and,

FIG. 6 is an end elevational view of the door handle of FIG. 1.
